UNITED STATES PATENT OFFICE.

JOHN S. LEONHARDT, OF DETROIT, MICHIGAN.

DESIGN FOR A BROOM OR MOP HOLDER.

47,927.

Specification for Design.

Patented Oct. 5, 1915.

Application filed March 20, 1915. Serial No. 15,967. Term of patent 7 years.

To all whom it may concern:

Be it known that I, JOHN S. LEONHARDT, a citizen of the United States, residing at Detroit, in the county of Wayne and State of Michigan, have invented a new, original and ornamental Design for Broom or Mop Holders, of which the following is a specification, reference being had to the accompanying drawing, forming a part thereof.

Figure 1 is a perspective view of a broom or mop holder, showing my new design; and Fig. 2 is a rear elevation.

I claim:

The ornamental design for a broom or mop holder, as shown.

JOHN S. LEONHARDT.
